CLAIM

The ornamental design for a set of male figures for decoration, as shown and described.

DESCRIPTION

FIG. 1 is a front elevational view of the set of male figures for decoration showing my new design.

FIG. 2 is a rear elevational view thereof.

FIG. 3 is a left side view thereof.

FIG. 4 is a right side view thereof.

FIG. 5 is a top plan view thereof.

FIG. 6 is a front elevational view of two of the elements shown attached for clarity of disclosure;

FIG. 7 is a rear elevational view of FIG. 6;

FIG. 8 is a left side elevational view of FIG. 6;

FIG. 9 is a right side elevational view of FIG. 6;

FIG. 10 is an enlarged top plan view of FIG. 6; and,

FIG. 11 is a front elevational view of two of the elements in an alternate attached condition for clarity of disclosure.
